UNITED STATES PATENT OFFICE

EDWIN H. PERCY, OF FORT BRAGG, CALIFORNIA, ASSIGNOR, BY MESNE ASSIGNMENTS,
TO THE PRESCOTT COMPANY, A CORPORATION OF MICHIGAN

SAW MILL LOG CARRIAGE MACHINERY

Application filed January 3, 1924, Serial No. 684,105. Renewed August 16, 1928.

This invention relates to saw mill machinery and particularly pertains to the means employed for "dogging" a log and aligning it on the carriage with respect to the line 5 of cut of the saw.

Prior to my invention it was proposed to equip saw mill carriages with pneumatically operated "dogging" devices and to provide a centralized control for such devices located 10 convenient to the carriage operator's station adjacent the setting mechanism on the carriage; the object being to expedite the "dogging" operations and to reduce the number of attendants on a carriage to a minimum.

In carrying out this proposed arrangement it was necessary to install a telescopic pipe beneath the platform of the carriage to serve as means of communication between the air storage tanks and the air cylinders by 20 which the "dogging" devices were operated. Also it was necessary to arrange a network of valve controlled piping and air hose between the "dogging" devices and the point of control to accomplish the centralized control idea.

The arrangement just outlined has not proven entirely practical from the viewpoint of efficiency and economy for various reasons, chief among which are, the very expensive equipment necessary to create and maintain sufficient air pressure with which to operate the various devices; the excessive amount of power required to operate the equipment; and the low degree of efficiency 35 due to the impossibility of maintaining the piping, its control valves and the air cylinders leak-proof.

With the object in view of overcoming the disadvantages and shortcomings of the arrangement just described and other prior methods, the present invention embodies the use of improved electrically driven "dogging" devices and a centralized electrical control therefor.

In carrying out this object I provide a battery of efficient "dogging" devices which are mounted on the usual knees on the head blocks of the log carriage. The "dogging" devices are equipped with electric driving 50 motors, the operation of which is controlled

from a central point whereby the operator of setting mechanism may exercise complete control over them at any time.

The battery of "dogging" devices includes what I prefer to term a "hook" dog. This 55 device, under my method, is operated when a log is placed on the carriage to grip the same and draw it tightly against the head blocks and knees and hold it in this position while one side of the log is being sawed flat. The 60 "hook dog" is so designed that when engaged with a log it will absolutely prevent endwise movement of the log during the sudden changes in direction of motion of carriage, and it will also prevent the log from "rolling" 65 into the saw during the operation of the carriage.

The remainder of the battery of machines is composed of what I prefer to term "tong dogs". These dogs are also mounted upon 70 the usual knee frames and equipped with electric driving motors.

The "tong dogs" are operative to engage the top and bottom of a log or timber on the carriage in a manner which will not mar what is termed the back-board. The "tong dogs" are employed to grip and firmly hold a log in one position on the headblocks and against the knees after one side of the log has been 75 sawed flat and turned down on the head-blocks.

No claim is made herein for the "tong dogs", these "tong dogs" being disclosed and claimed in my pending application for power 80 operated dogging mechanism, filed November 20, 1924, Serial No. 750,968.

Further, I also equip certain of the knees with very simple and efficient tapering devices which are electrically operated. These 85 devices permit a tapering log to be quickly aligned with respect to the line of cut of the saw. Also they permit the cutting of timbers to any desired degree of taper.

As before stated all of my improved equipment is electrically driven and the controls for the same are arranged convenient to the station of the operator so that he may place in or out of operation any one or group of devices at his option.

By the use of my improved "dogging" de- 100

vices and the electric drive and control therefor, I am enabled to greatly reduce the operating cost of a log carriage, as but a small amount of power is required and one operator may efficiently control and operate the various mechanisms. Also, the initial cost of installation of my equipment is very low as compared with prior arrangements.

One form which the present invention may assume is exemplified in the following description and illustrated by way of example in the accompanying drawings, in which:—

Fig. 1 is a diagrammatic view in plan of a saw mill log carriage, disclosing my improved apparatus mounted thereon.

Fig. 2 is a diagrammatic view of the electrical equipment of my apparatus and showing the controls therefor.

Fig. 3 is a perspective view of one unit of my improved apparatus and is what I herein-after term a "hook dog".

Fig. 4 is a side elevation of the unit disclosed in the preceding figure and showing the operating arms thereof in various positions.

Fig. 5 is a perspective view of another unit of my improved apparatus which is herein-after termed "tong dog".

Fig. 6 is a side elevation of the unit disclosed in the preceding figure disclosing its construction.

Fig. 7 is a fragmentary view of the "tong dog" showing the operating arm thereof in position engaging a log.

Fig. 8 is an enlarged view of the tapering mechanism and disclosing its connection with the setting rack of one of the knee frames.

Fig. 9 shows a detail view of a solenoid brake-releasing device employed in connection with the motors.

Referring more particularly to the accompanying drawings, 10 indicates a saw mill log carriage of usual construction. In the present instance this carriage is shown as equipped with a running gear comprising a plurality of transverse axles 11 which are journaled in suitable bearings 12 fixed on the longitudinal sills 14 of the carriage 10. The ends of these axles are fitted with wheels 15 which are adapted to run on rails arranged in parallelism with the path the carriage is intended to travel. The carriage may be driven by any suitable form of driving mechanism, but as this forms no part of the present invention, it is not shown.

The log carriage 10 is equipped with a plurality of head blocks 16 which, as in usual practice, are rigidly fixed transversely of the carriage in parallelism and at spaced distances apart. Although in this instance only four head blocks are shown, it is to be understood that any number may be employed as the number and spacing of the head blocks depends entirely upon the length of the car-

riage and the character and size of the logs to be sawed.

The head blocks 16 are formed with parallel guide rails 17 upon which the knee frames 18 of "dogging" devices indicated at A, B, C, and D in Fig. 1, are supported and guided for movement transversely of the log carriage. The knee frames 18 of all these devices are alike in construction and are formed at one end with a vertical aligning face 20. In practice the faces 20 of the knees 18 cooperate with the surfaces of the head blocks to permit a log to be properly aligned with respect to a saw (not shown) with which the carriage is intended to co-act. As stated, the knees 18 are guided on the head blocks for movement transversely of the carriage so that they may be operated to advance or retract a log with respect to the line of cut of the saw. For accomplishing this a setting shaft 21 is arranged longitudinally of the carriage beneath the head blocks. This shaft is fitted with pinions 22 which are in constant mesh with racks 23 fitted at the bottoms of the knee frames 18. The setting shaft 21 is operated by a set works 24 conventionally illustrated in Fig. 1. This set works is operated by any suitable power such as belt or electric motor. This set works is reversible and when placed in operation will, through the medium of the setting shaft and the pinions thereon, advance or retract the knees with respect to the line of cut of the saw.

Hook dog

The dogging device indicated at C in Fig. 1 is what I prefer to term a "hook dog". In practice this device is actuated when a log is first placed on the carriage to grip the top of the log and hold it tightly against the headblocks and knees while the carriage is operated to run the log through the mill until one side of the log is sawed flat. The log is then turned to place the flat side against the headblocks.

Reference being had to Figs. 3 and 4 where the "hook dog" is most clearly illustrated, it will be seen that this device includes a base 26 which is mounted on the knee frame between upstanding lugs 27. The ends of the base 26 are fitted with adjusting screws 27a which permit the base to be adjusted toward and away from the aligning face 20 of the knee while the base may then be clamped by means of cap screws 28 which extend through slots in the base and are threaded into the knee 18.

Bearings 29 are formed at the sides of the base approximately centrally thereof and serve as journals for a short shaft 30. A sub-frame 32 is positioned above the base and is formed with a downwardly projecting bearing 33 which is pivoted on the short shaft 30 for a very limited amount of vertical swinging movement. The upward swinging of the

subframe is limited by a chain 34 which connects the front end of the subframe to the knee. Downward movement of the member 32 is resisted by a comparatively heavy compression spring 35 which is interposed between the underface of the subframe and the base 26.

The subframe 32 carries a reversible electric driving motor 36, the shaft of which is fitted with a pinion 37. This pinion is in constant mesh with a gear 38 which is fixed on a shaft 39 journaled in bearings 40 on the subframe.

The movable end of the subframe 32 is bifurcated to accommodate a pinion 41 which is fixed on the shaft 39, and an operating gear 42 with which the pinion 41 is in constant mesh.

The operating gear 42 is fitted with a radially extending crank arm 43. The inner end of a dog arm 44 pivotally connects to the outer end of the crank arm 43 by means of a friction joint 42a. The outer end of the dog arm is slightly arcuate and is fitted with a downwardly projecting spike 45 which is adapted to be engaged with the top of a log positioned on the head blocks.

To limit the swinging movement of the dog arm 44 with respect to the crank arm 43, I form the inner end of the dog arm with lugs 46 and 47 which extend from opposite sides of the arm and are engageable with the peripheral face of the operating gear 42.

The dog arm 44 is guided between a pair of rigid guide members 48 which are securely bolted to opposite sides of the knee 18. A resilient pad 49 is secured between the members 48 at the upper ends thereof to serve as a bumper for the arm 44.

The motor 36 is equipped with a brake 50. This brake includes a pair of brake shoes 51 which are normally held in frictional contact with a brake drum 52 fixed on the motor shaft. The lower ends of the brake shoes are pivoted to the subframe, the upper ends are loosely connected by a rod 53 which is fitted with a spring 54 for normally holding the shoes in contact with the drum. The brake shoes are automatically disengaged from the drum when the motor is started by a solenoid actuated brake releasing device such as is illustrated in Fig. 9. The solenoid is automatically energized when the motor circuit is closed and causes the brake releasing device to release the brake shoes from engagement with the drum.

In operation, when the motor 36 is started, the operating gear 42 is caused to revolve, thus downwardly swinging the crank arm 43 and the dog arm 44 until the spike on the operating rod engages the log. The crank arm continues to swing and when the lug 47 on the operating arm abuts against the gear 42, acts to draw the dog arm downwardly to force the spike into the top of the log and pull

the log tightly against the head blocks and knees. The motor circuit is then opened and the brake grips the drum on the motor shaft to prevent the latter from turning. This holds the dog arm stationary and prevents the log from rolling.

In operation, when the motor 36 is started, the gear 42 is given a partial turn carrying the crank arm 43 and dog arm 44 downwardly until the spike on the dog arm strikes the log. The dog arm thereupon comes to a stop and the crank arm continues to swing until the lug 47 on the arm 44 abuts against the gear 42, as shown in dotted lines, Fig. 4. This acts to draw the dog arms downwardly and force the spike into the top of the log, and at the same time pull the log tightly against the knee. When the dog reaches its limit of movement the motor will come to a stop on account of the overload. The operator then opens the motor circuit and simultaneously the brake shoes 51 become set, thus holding the dog against accidental displacement. When it is desired to release the dog, the motor through a reversing switch presently to be described is operated in the opposite direction, causing the gear 42 to be turned to the right as viewed in Fig. 4. The crank arm will first tend to thrust the dog arm upwardly, thereby removing the spike from the log, and when the dog arm has been raised to a position where it strikes the buffer 49, it will be straightened out with respect to the crank arm, and the lug 46 will strike the base of the gear 42, thus stopping further movement of the gear and stalling the motor.

The "hook dog" just described is particularly efficient when used to "dog" extremely large logs and logs with heavy bark. The device is intended to grip and hold the log on the head blocks until one side of the log has been sawed flat. The "dog" is then released and the log is turned to dispose the flat side thereof on the surfaces of the head blocks. When this has been done the "tong dogs" A, B and D are brought into operation to hold the log against the knee blocks until it has been sawed up.

Tong dogs

The "tong dogs" are identical in construction and operation. Reference being had to Figs. 5, 6 and 7 where one "tong dog" is clearly illustrated, it is seen that the device includes a base 55. This member is bolted to the knee 18 between upstanding lugs 56. A trunnion 57 projects from each side of the base and constitute pivotal connections between the lower ends of vertical links 58 and the base. The upper ends of the links are pivotally connected to the rear end of an upper dog arm 59 which is fitted at its forward end with a downwardly curved hook point 60. The arm 59 carries a reversible

electric driving motor 61, the shaft of which is fitted with a pinion 62. This pinion is in constant mesh with a gear 63 which is fixed on a shaft 64. A pinion 65 is also fixed on this shaft and is in constant mesh with a vertically disposed rack 66 which is pivoted at its lower end on a lower dog arm 67. The rack is held in mesh with the pinion by means of guide rollers 68 which are carried between 10 a pair of plates 69 which are pivoted on the shaft 64.

The lower dog arm is formed with a slotted rear end which is mounted on one of the trunnions 57. The forward end of the arm 15 is fitted with an upwardly curved hook point 70.

At their forward ends, both of the dog arms are fitted with projecting studs 71 which engage a guideway 72 formed in a 20 guide member 73. This member is rigidly secured to the knee and is fitted at its upper end with a coil spring bumper 74 for cushioning the upstroke of the upper arm.

To actuate the dog arms to grip a log, the 25 motor 61 is started. This motor, through the pinion 62 and gear 63 revolves the pinion 65 and causes the latter to travel down the rack 66 until the hook point 60 engages a log. The pinion will then cause the rack to travel upwardly until the hook point 70 engages the log. When both the hook points have gripped the log, the circuit of the motor 61 is opened. The shaft of this motor is fitted with a brake 30 drum for cooperation with a spring tension 35 brake 75^a, which, when the current to the motor is shut off, will resist rotation of the motor shaft and thereby hold the dog arms in position. By reversing the motor 61 the hook points on the dog arms may be disengaged 40 from the log and returned to normal position.

Tapering devices

When a tapered log is to be sawed, it is 45 essential that the small end be positioned to approximately line up the longitudinal center of the log substantially parallel with the line of cut of the saw. To accomplish this, I have provided means, here termed the tapering devices, for shifting the knees carrying 50 the "tong dog" devices transversely of the carriage independently of each other and of the set works.

Each of the knees carrying the "tong dogs" 55 is fitted with a tapering device such as generally indicated at 75 in Fig. 6, but most clearly shown in Fig. 8. This device comprises a screw feed shaft 76 which is journalled at its ends in bearings 77 on the base 55. At its rear end this feed shaft is fitted with a gear 78 which is in constant mesh with a pinion 79 fixed on the shaft of a reversible electric motor 80. This motor is supported by the base plate and is equipped with a spring tension brake 81. The gear 78 is held into driv-

ing engagement with the shaft by a helix collar 82 which is held in engagement with a helix hub 83 on the gear 78 by a compression spring 84. Ordinarily the connection described between the gear 78 and the feed shaft is sufficient to cause the gear to revolve the shaft, but should the shaft become locked against turning movement, the gear will rotate free of the shaft. 70

A feed nut 85 is threaded on the feed shaft 75 and is formed with a downwardly extending arm 86. A substantially horizontally disposed link 87 connects this arm with the setting rack 23 which is slidably mounted in the bottom of the knee frame. It is obvious that 80 when the rack is held stationary by the setting pinion 22 on the setting shaft 21, and the motor 80 is started, the feed shaft will advance through the feed nut and consequently advance the knee frame and dogging mechanism transversely of the carriage frame independent of the rack 23. 85

When the knee frame is to be returned to normal position in alignment with the other knees, the direction of operation of the motor 90 is reversed to retract the feed screw through the feed nut until the end of the latter abuts against one of the stationary stops on the base. The screw feed shaft is then locked against rotation and the gear 78 will rotate 95 free of the shaft until the motor is stopped.

The feed nut 85 is fitted with a pointer 88 which is adapted to cooperate with a calibrated indicator plate 89 fixed on the base to indicate the amount of transverse movement 100 of the knee or "tapering" of the log so that the operator may advance the knee an exact amount and the tapering can be carried out to any fraction of an inch. This is particularly desirable when sawing timber into tapered telephone and like poles where specifications frequently call for odd dimensions. 105

The "hook dog," the "tong dogs," and the "tapering devices," as described, are all electrically driven and may all be controlled from 110 a central point convenient to the operator of the log carriage.

Each dog and tapering device has an individual motor which is of the reversible type. The usual carriage will require but one hook 115 dog. It is controlled separately from the tong dogs by its own switch, which, as here shown, is in the form of a foot-operated reversing switch located conveniently to the set-works operator. Should it be desired for any 120 reason to use more than one hook dog on a carriage the additional one may conveniently be controlled by one and the same switch. The tong dogs, of which there are usually a plurality on a carriage, are all controlled by 125 a single switch, which likewise is here shown in the form of a foot-operated reversing switch located conveniently to the set-works operator. If desired, an individual cut-out switch may be employed for each motor cir- 130

cuit operating the tong dogs, in case it should be desired to stop the operation of one pair of tong dogs without interfering with the operation of the others. Each tapering device motor has a cut-out switch located conveniently to the operator, and all of the tapering device motors are under control of a single reversing switch, as in the case of the tong dogs motors.

- 10 The control is diagrammatically shown in Fig. 2 where the letter E indicates the driving motor of the set works, should it be driven this way, the letter F indicates the motor of the "hook dog" device, and the letter H indicates the driving motors of the "tong dogging" devices. The motors of the tapering devices are indicated at J. The source of electrical energy for all of these motors is indicated at K. In practice, the log carriage is driven by steam or cable and the source of supply for the dogging and other motors may be derived from a trolley or other collector device or from the same source as the set works motor.
- 15 The motor E of the set works when used is connected by conductors 90 to a non-reversing switch 91 which in turn is connected to the source of electrical energy. The switch 91 when the set works is driven by electric motor is located within convenient reach of the operator's seat on the carriage which is indicated at 92 in Fig. 1.

20 The driving motor F of the "hook dog" is connected by conductors 93 to a reversing switch 94 which in turn is connected to the source of electrical supply. The reversing switch is preferably located beneath the platform of the carriage and operatively connected to a foot pedal 94^a shown in Fig. 1 which is located on the carriage in position where the set works operator may control the operation of the "hook dog" from his seat.

25 The motors H of the "tong dogs" are each connected by pairs of conductors 95 to double pole single throw switches 96. These switches connect to a pair of main lead conductors 97 which are connected to a reversing switch 98. This switch is connected to the source of electrical energy. The switches 96 are preferably located in a cabinet or fuse box 99 which is placed adjacent the operator's seat on the log carriage as shown in Fig. 1. The reversing switch 98 is preferably located beneath the carriage platform and operatively connected to a foot pedal 100 which is shown in Fig. 1 as located within convenient reach of the set works operator's station.

30 It is obvious that by the provision of the double pole switches 96 and a single main reversing switch 98, the operator may cut-out any one of the "tong dogs" by simply opening the switch 96 in the circuit of the "tong dogs" which he wishes to remain inoperative. By closing the reversing switch 98 the circuits of the motors in which the

switches 96 are closed will be completed and the "tong dogs" operated thereby will be placed in operation.

35 The motors J of the tapering devices are each connected by pairs of conductors 101 to double pole single throw switches 102. These switches connect to a pair of main lead conductors 102^a which are connected to a reversing switch 102^a. This switch is connected to the source of electrical energy. The switches 102 are preferably located in the fuse cabinet as indicated at 99. The reversing switch 102^a may be located under the platform similar to switch 96 and operated by a pedal 103.

40 In actual operation, when a log is delivered to the carriage, the operator closes the circuit of the driving motor of the "hook dog," which acts to grip the log and draw it tightly against the head blocks and the knees. The operator may then operate the set works to align the log with respect to the line of cut of the saw. The carriage is then placed in operation until the one side of the log is sawed flat. The "hook dog" is then released by reversing its motor and the log turned to dispose the flat side on the head blocks. The operator may then bring into operation all of the "tong dogs" to grip the top and bottom of the log and hold it against the knees. Should it be necessary to taper the log to line it up, the necessary switches may be closed to operate one or more of the tapering devices to advance the selected knee to bring the longitudinal center of the log substantially in alignment with the line of cut of the saw. The carriage may then be placed in operation until the log is completely sawed up.

45 By reversing the operation of the driving motors of the "tong dogs" by means of the switch 98, the dogs may be released from engagement with the log and returned to an inoperative position. The switches of the various tapering device motors may then be closed to return the advanced knees back into alignment with the others. By providing the pedals for operating the reversing switches with the "hook dog" motors and "tong dog" motors, the operator is enabled to exercise control over these devices at any time. Also, the cut-out switches of the "tong dog" motors are within convenient reach of the operator that he may cut-out any one, any group, or all of the "tong dogs" at his option. The tapering device motors may also be operated from the operator's seat so that a log may be lined up quickly and with ease.

50 While I have shown the preferred form of my invention as now known to me, I wish it understood that various changes may be made in its construction without departing from the invention as defined in the appended claims.

55 Having thus described my invention, what

I claim and desire to secure by Letters Patent is:—

1. A dogging device for saw mill carriages comprising a knee frame adapted to be slidably mounted on a head block and having a vertical aligning face, an operating gear journaled on said frame and having a radially extending crank arm, a vertically swinging dog arm pivoted at one end to said crank arm and having means at the other end for engaging a log on said head block adjacent said aligning face, means to limit pivotal movement of the dog and a high speed motor on said frame for driving said operating gear to swing said arm.
2. A dogging device for saw mill carriages comprising a knee frame adapted to be slidably mounted on a head block and having a vertical aligning face, an operating gear journaled on said frame and having a radially extending crank arm, a vertically swinging dog arm pivoted at one end to said crank arm and having means at the other end for engaging a log on said head block adjacent said aligning face, a high speed motor on said frame for actuating said operating gear to swing said arm, and lugs at the inner end of said arm engageable with the periphery of said operating gear for limiting the swinging movement of said dog arm with respect to the said crank arm whereby the arm will be drawn downwardly and inwardly with respect to said aligning face when the operating gear is driven in one direction.
3. A dogging device for saw mill carriages comprising a knee frame adapted to be slidably mounted on a head block and having a vertically aligning face at one end thereof, an operating gear journaled on said frame and having a radially extending crank arm, a vertically swinging dog arm pivoted at one end to the said crank arm and having means at the other end thereof for engaging a log positioned on the head block adjacent said aligning face, a high speed motor carried by the frame and operatively connected to said operating gear for actuating said dog arm, and lugs formed at the inner end of said dog arm engageable with the peripheral surface of said operating gear for limiting the swinging movement of said dog arm with respect to the said crank arm whereby the arm will be drawn downwardly and inwardly with respect to said aligning face when the operating gear is driven in one direction, said motor being reversible.
4. In combination with a head block, a knee slidably mounted thereon, a setting mechanism for advancing or retracting said knee along said block, said setting mechanism including the driving shaft having a pinion thereon, a rack slidably mounted at the bottom of said knee and in constant engagement with said pinion, a screw shaft carried on the frame, a feed nut on said shaft connected

with said rack and normally constituting a rigid connection between said knee frame and said rack whereby they will move in unison, and means for operating said screw shaft for advancing or retracting the feed nut therealong whereby to advance or retract the knee along the head block independently of the rack, said means including a driving motor supported by the knee, a pinion on the shaft of said motor engageable with the gear on said screw shaft, and a connection between said last named gear and said screw shaft whereby the gear will be free to turn on said shaft when the shaft is locked from rotation.

5. The combination with a saw-mill carriage having the usual knee set-works, of power means for individually adjusting each knee for tapering a log, comprising a rotatable shaft on the knee, a member fixed with relation to a part set by the set-works mechanism and engaging the shaft so as to cause the latter to move longitudinally when rotated, and a reversible motor for driving said shaft.

6. The combination with a saw-mill carriage having the usual knee set-works, of power means for individually adjusting each knee for tapering a log, comprising a rotatable shaft on the knee, a member fixed with relation to a part set by the set-works mechanism and engaging the shaft so as to cause the latter to move longitudinally when rotated, and a reversible motor for driving said shaft, and a slip connection between the motor and shaft.

7. The combination with a saw mill carriage having the usual knee set-works, of power-operated means for individually adjusting each knee for tapering a log, comprising a screw shaft, a feed nut thereon, a motor for driving the shaft, a pointer on the feed nut, exposed to the view of a central set-works operator, and an indicator plate fixed to the base of the knee and co-operating with said pointer.

8. In a saw mill carriage, a knee, a hook dog thereon comprising a single log engaging arm mounted to swing in a vertical plane, an oscillatory member on which the log engaging arm is pivotally mounted, means to limit the pivotal movement of the log engaging arm in either direction, and a high speed reversible motor and reduction gearing for driving said oscillatory member in either direction.

9. In a saw-mill carriage, a knee, a hook dog thereon comprising a single log engaging arm mounted to swing in a vertical plane, a high-speed reversible motor carried by the knee, a driving connection between the motor and log engaging arm to cause the latter to swing in either direction, said driving connection including a mounting for the log engaging arm whereby the latter may turn on

a pivot after it strikes a log, and means for limiting the pivotal movement.

10. A sawmill carriage having head blocks, knees slidably mounted on said head blocks, 5 a set shaft common to all the knees, driven members geared to the set shaft, there being one driven member for each knee, adjustable connections between the driven members and the knees, an electric motor mounted on each 16 knee and gearing between each electric motor and the adjustable connection of its knee, said gearing including a slip connection.

EDWIN H. PERCY.
